(57) **CLAIM**

The ornamental design for a structural member, as shown and described.

DESCRIPTION

The structural member may be used as a brace, a truss or a joist.

FIG. 1 is a top plan view of a structural member showing, our new design broken away in the middle and in both directions it being understood that the pattern of triangular openings is repeated uniformly throughout;

FIG. 2 is a bottom plan view thereof;

FIG. 3 is a left end view thereof;

FIG. 4 is a front side view thereof;

FIG. 5 is a right end view thereof;

FIG. 6 is a rear side view thereof; and,

FIG. 7 is a top, end and side perspective view thereof.
